UNITED STATES PATENT OFFICE.

WILLIAM J. BENDALL, OF GLOBE, ARIZONA.

FLY-PAPER HOLDER.

1,097,838.

Specification of Letters Patent. Patented May 26, 1914.

Application filed September 15, 1910. Serial No. 582,198.

To all whom it may concern:

Be it known that I, WILLIAM J. BENDALL, a citizen of the United States, residing at Globe, in the county of Gila and State of Arizona, have invented certain new and useful Improvements in Fly-Paper Holders, of which the following is a specification.

This invention relates to a device for holding sticky fly-paper, so that the same will not be blown about by wind.

An important object of this invention is to provide a holder of the above character, which is simple in construction, durable and cheap to manufacture.

15 A further object of this invention is to provide a structure for holding fly paper, which will permit of the maximum amount of sticky surface to be exposed to the ready access of flies.

20 In the accompanying drawings forming a part of this specification, and in which like numerals are employed to designate like parts throughout the same, Figure 1 is a perspective view of the holder, Fig. 2 is a 25 longitudinal section taken on line 2—2 of Fig. 1, and Fig. 3 is a cross-sectional view taken on line 3—3 of Fig. 1.

In the drawings wherein is illustrated a preferred embodiment of my invention, the 30 numeral 1 designates a section of flat sheet-metal, serving as a handle portion for the device. The section 1 is provided midway of its ends with an extension 2, having an aperture 3 formed therethrough, whereby 35 the extension 2 may be readily connected with a suitable cord when it is desired to suspend the device, as will be explained hereinafter. The section or handle portion 1 has formed thereon a preferably rectangular open frame 4, which may be termed for 40 the sake of clearness, a stationary frame. The outer longitudinal edges and the lower outer transverse edge of this stationary frame are provided with flanges 5, which 45 are connected to form in effect a continuous flange.

Adapted to coöperate with the stationary open frame 4, is a movable preferably rectangular open frame 6, having its outer longitudinal edges and its lower transverse edge provided with flanges 7, which form in effect a continuous flange. The flanges 5 of the stationary frame extend toward the movable frame 6 and fit snugly between the 55 flanges 7, as shown. The inner longitudinal edges and the upper and lower inner trans-

verse edges of the frame 6 are provided with flanges 8, forming in effect a continuous rectangular flange. The flanges 8 extend in the same direction as the flanges 7; that is toward the stationary frame 4. The upper end of the frame 6 is connected with the section 1 by a hinge 9, one leaf of which is suitably secured to the plate 1, and the other leaf to the frame 6. The lower end of the stationary frame 4 has a spring catch 10 suitably secured thereto, which extends downwardly and then upwardly for engagement with the lower end of the movable frame 6 for releasably holding the frame 6 in its 70 closed position.

In the use of the holder, a sheet of sticky fly-paper 11 is arranged within the stationary frame 4, and the movable frame 6 brought into engagement with said stationary frame. The inner flanges 8 engage the sheet of fly paper and securely clamp the same against the stationary frame, it being understood that the flanges 8 engage the margin of the fly-paper which is always left 80 free from sticky material. The flanges 5 of the stationary frame also serve to prevent the displacement of the fly-paper. The outer flanges 7 of the frame 6 engage the flanges 5 for preventing the displacement of the movable frame 6. The fly-paper is thus securely held in the device, which may be laid upon a table or the like. In the use of the device, two sheets of fly-paper may be placed together so that their sticky surfaces will be 85 exposed or outermost. These two sheets are then placed within the holder, and owing to the fact that both the stationary and movable frames are formed open, the flies may have ready access to the two sticky surfaces. 90 When the holder is employed in connection with two sheets of fly-paper arranged as above stated, said holder is suspended by a suitable cord or the like having connection with the extension 2. 95

I wish it understood that the form of my invention herewith shown and described, is to be taken as a preferred example of the same, and that certain changes in the shape, size and arrangement of parts may be resorted to without departing from the spirit of the invention or the scope of the subjoined claim.

Having thus fully described my invention what I claim as new and desire to secure by Letters Patent, is:—

A device of the character described, in-

cluding a relatively stationary section of sheet metal stamped to provide an upper handle portion having an open rectangular frame formed thereon and depending therefrom and provided with an upstanding U-shaped flange extending inwardly and along the lower horizontal end and vertical sides of the open rectangular frame, a movable rectangular frame to be arranged opposite the 10 stationary rectangular frame and provided with an outer inwardly extending upstanding U-shaped flange extending along the outer lower horizontal and vertical edges of said outer rectangular frame to receive therein 15 the first-named U-shaped flange, said outer movable rectangular frame being provided

with an inner inwardly extending rectangular flange arranged in spaced relation to the outer U-shaped flange carried by the outer movable frame, a hinge attached to the handle and having its outer leaf off-set and attached to the upper end of the outer movable frame, and a spring catch attached to the lower end of the stationary frame, and engaging the lower end of the outer movable frame. 20 25

In testimony whereof I affix my signature in the presence of two witnesses.

WILLIAM J. BENDALL.
